UNITED STATES PATENT OFFICE

157,452

EARTH MOVING VEHICLE

Eddie B. Wagner, Portland, Oreg.

Application July 14, 1948, Serial No. 147,570

Term of patent 14 years

(Cl. D14—3)

To all whom it may concern:

Be it known that I, Eddie B. Wagner, a citizen of the United States, residing at Portland, in the county of Multnomah and State of Oregon, have invented a new, original, and ornamental Design for an Earth Moving Vehicle, of which the following is a specification, reference being had to the accompanying drawings, forming a part thereof.

In the drawings:

Fig. 1 is a side elevation of the earth moving vehicle, with the upper track tower section raised;

Fig. 2 is a rear elevation of the machine with the upper track tower section lowered;

Fig. 3 is a side elevational view as seen from the side opposite that shown in Fig. 1 but with the upper track tower section in lowered position;

Fig. 4 is a front elevation with the upper track tower section raised;

Fig. 5 is a plan view with the upper track tower section raised.

I claim:

The ornamental design for an earth moving vehicle, substantially as shown.

EDDIE B. WAGNER.
